UNITED STATES PATENT OFFICE.

JOHN E. ANDRECK, OF WARREN, CONNECTICUT.

AUTO-SIGNAL.

1,384,112.

Specification of Letters Patent. Patented July 12, 1921.

Application filed January 24, 1921. Serial No. 439,534.

To all whom it may concern:

Be it known that I, JOHN E. ANDRECK, a citizen of the United States of America, residing at Warren, Litchfield county, Connecticut, have invented a new and useful Improvement in Auto-Signals, of which the following is a specification.

The main object of my invention is to provide a simple device which may be readily operated from the front seat to indicate the intended movement of the car. I have also sought to provide a construction which may serve as a signal by day as well as by night. I have also sought to construct the apparatus so that a single light will serve as a rear light and also illuminate the direction signals as well as the number or license plate.

Figure 1 illustrates the apparatus diagrammatically;

Fig. 2 is a perspective view of the signal apparatus *per se*;

Fig. 3 is a side view and partial section, showing a fragment of the signal device and also showing an operating handle:

Fig. 4 is a horizontal section and plan of the same;

Fig. 5 is an end view of the mechanism for operating the signal hands.

Fig. 6 is a fragmentary side view showing a modified operating mechanism.

The box or casing 6 is preferably divided into two parts by a partition 7. A lamp 8 of any suitable type is mounted in the rear compartment in line with the red lens 9, and above and in rear of the license or number plate 10. An opening 11 is provided in the bottom of the compartment, so that the light from the lamp can shine upon the number plate.

On the top of the box is hinged a hand 12 which, in the traveling position, lies flat against the top of the box, covering the opening 13. This hand 12 may have on its lower surface the word "Stop" or similar direction signal, which is adapted to be displayed when the hand is raised, as shown in the dot and dash lines of Fig. 2. At night the light from the lamp may shine through the opening 13 and illuminate this hand and direction signal. At one or both sides of the box is mounted a hand, such as 14, preferably hinged and normally covering the opening, such as 15, through which light may shine to illuminate it and also any direction device that may be on the back of the hand

when the hand is extended. The signal box may be mounted in any convenient place on the car and operated in various ways. It is preferably mounted at the rear so as to provide a rear light and also illuminate the license plate.

In the form shown in Figs. 1 to 4 inclusive, I have provided for manual operation, as will be hereinafter understood. Each of the indicating hands is operated in substantially the same manner, and it will therefore be necessary to describe only one connection. For convenience I will describe the connection for the right hand indicating member 16. Extending inwardly from the pivot or hinge of the hand is an arm 17, rigidly connected with the hand and connected to the lever 18 by a pin and slot 19. The lever 18 is provided with a spring 20 about its pivot, which spring 20 normally tends to keep the hand 16 in its closed or non-indicating position. Preferably the link connections are such that the hand cannot be swung from the outside. To operate the lever 18 I provide a plunger 21, having a finger 22 adapted to engage the short end 23 of the lever when the plunger is pulled forwardly. A spring 24 tends to keep the plunger 21 in the rearward position, as shown in Fig. 4. By pulling the plunger 21 forwardly in any suitable manner the finger 22 engages the short arm 23 of the lever and moves it to the dot and dash position so as to swing the hand 16 outwardly and indicate that the car is about to turn to the right. To operate the plunger 21 I provide a handle 25 and a connecting link or shaft 26 which, if necessary, may be of the jointed universal type. The rod 27 of this connecting link or shaft is guided in a support 28 and connected to a pin 29 in the slotted end of the handle 25 and held yieldingly in the position of Figs. 3 and 4 by a spring 30. The rear end of the handle is provided with a cam-like shoulder 31, adapted to co-act with the outer end of the support 28. When the handle 25 is rocked on its pivot 29, the cam 31 rides over the end of the support 28 and pulls the rod 27 and connection 26 forwardly, so that the finger 22 will engage the arm 23 and operate the hand 16. The end of the handle and the support 28 are so constructed that the handle will remain in this position, with the hand 16 extended, until the handle 25 is turned down, so as to release the rod 27 and the connection 26 and permit the spring 20 to return the

hand to its closed position. By turning the handle 25 about the axis of the rod 27, the finger 22 may be brought opposite the operating lever for the desired signal. The 5 driver may readily perform this operation in anticipation of an intended move and then, at the proper instant, tilt the handle about the axis 29, so as to operate the desired signal.

10 Supporting links, such as 32, may be connected to the shaft 26 at intervals and mounted on brackets 33 where desired, so as to support the shaft with a minimum of friction and at the same time permit the 15 shaft to move at an angle.

Instead of having a single operating handle, as in the form shown, it should be understood that I contemplate the provision of separate operating devices, such as pulls 20 or pedals, for each signal hand. In the form shown in Fig. 6, a pedal 25' is connected by a wire or chain 26' to the short arm 23' of an operating lever. A lever 27' may be interposed between the wire 26' 25 and the pedal 25' and a spring 30' may be provided for holding the parts in the normal position of rest. It should be understood that other changes may be made in the 30 construction without departing from the spirit or scope of my invention.

It will be seen from the foregoing that at night but a single lamp is required to furnish the ordinary rear light and to illuminate any one of the signals, as well as the 35 number or license plate. In the daytime, of course, the lamp is not needed but the license plate is displayed to the rear and the signals are adapted to be operated when necessary.

40 It will be understood, of course, that I do not wish to be limited to the use of a single lamp for illuminating all of the signals or to a single lamp to serve as a rear light and a signal illuminator, except as the same 45 may be specifically called for by the claims. I may use a reflector or reflectors 34 in the rear of the box to reflect light through the side, top, and bottom openings.

I claim:

50 1. In a signal device, a box having light passages on the top and on the sides, signal members having characters thereon and hinged to said box and normally covering said passages, a lamp within said box 55 adapted to illuminate said signal members, and means for selectively moving said signal members to uncover any one of said passages and permit the light to illuminate the characters on the moved signal member.

60 2. In a signal device, a box having light passages in the rear and on the sides and on the top and on the bottom, signal members hinged to said box and having signal characters thereon, said signal members 65 normally covering the top and side passages,

a lamp within the box adapted to illuminate all of said passages, and means for selectively extending any one of said signal members to uncover the corresponding passage and permit the light to illuminate the characters on said moved signal member. 70

3. In a signal device, a pivoted hand having an arm extending therefrom, a pivoted operating lever having a pin and slot connection with said arm whereby the arm 75 may be operated by said lever, means for operating said lever, and a spring for urging said hand into the inoperative position.

4. In a signal device, a hinged signal hand, a spring pressed plunger, a lever 80 adapted to be operated in one direction by said plunger, means of connection between said lever and said hand, and a spring for urging said hand into inoperative position.

5. In a signal device, a plurality of hinged 85 signal members, a rotatable and tiltable operating handle for operating said signal members, and means of connection between said handle and said signal members.

6. In a signal device, a plurality of hinged 90 signal members, a single operating handle, and means controlled thereby for selectively operating said signal members.

7. In a signal device, a plurality of movable signal members, a handle, rotatable 95 means of connection for selecting any one of said signal members, and means whereby the longitudinal movement of said connection operates the selected signal member.

8. In a signal device, a plurality of hinged 100 independently movable signal members, a rotatable plunger, means for operating said plunger, and means connected with said signal members whereby any desired signal member may be operated when said plunger 105 is rotated and longitudinally moved.

9. In a signal device, a movable member, an operating handle, a rotatable shaft having a rod hinged to said handle, means for moving said movable member and adapted 110 to be moved by said shaft when the latter is in one rotative position and to be undisturbed by said shaft when the latter is in another rotative position.

10. In a signal device, a movable member, 115 an operating handle, a rod hinged thereto, a support for said rod, a cam carried by said handle and co-operating with said support, means for connecting said movable member and rod for moving the member 120 when the rod is in one position, said means being disconnected when the rod is in another position.

11. In a signal device, a movable member, a support, a rod reciprocable and rotatable 125 in said support, an operating handle hinged to said rod and co-acting with said support, means for operatively connecting said movable member and rod when the latter is in one position, said operative connection be- 130

ing broken when the rod is in another position.

12. In a signal device, a pivoted indicator, manually operable means for moving said indicator in one direction, a spring for moving it in the opposite direction, said means being constructed to prevent movement of said indicator other than by said spring and by said manually operable means.

10 13. In a direction indicator, a box having an opening, a source of light within said box, a movable indicator normally closing said opening, a link mechanism inside of

said box for moving said indicator away from said opening, a spring for normally holding said indicator in position to cover said opening, said mechanism being constructed so as to prevent said indicator being operated except from within said box.

14. In an indicating device, a pivoted indicator having a slotted arm movable therewith, and a spring pressed lever having a pin operable in said slot, said parts normally preventing movement of said indicator.

JOHN E. ANDREGG.
